ELECTRIC FUSE HANDLE

Louis Ludwig, Brooklyn, N. Y.

Application October 27, 1934, Serial No. 750,246

2 Claims. (Cl. 200—113)

The invention relates to safety handles for electric fuses of the cartridge type. It has for its main object to provide an insulating handle which may be applied to any such fuse and which will effectively remove any danger of a person receiving shocks or burns while inserting or removing the fuse from the fuse contacts. Another object is to so construct the handle that the person's fingers will be guarded even when the fuse is either purposely or accidentally withdrawn from one contact only instead of from both contacts simultaneously, as sometimes happens.

A further object is to provide a handle which will not obscure the label on the fuse on which the fuse capacities are printed. A still further object is to so construct the handle that it will not interfere with the closing of the door of the fuse box. Additional objects are to provide a fuse handle of simple and strong construction, which can be manufactured and applied to the fuse at low cost.

These and various other objects and advantages will readily be understood from the accompanying drawing of a preferred embodiment of the invention in which, however, certain modifications may be made without departing from the appended claims. In the drawing

Fig. 1 is a side elevation of a standard cartridge fuse to which the handle has been attached,

Fig. 2 a similar view showing the finger grip in its other position,

Fig. 3 a front view of Fig. 1, and

Fig. 4 a plan view of the handle member.

While I am aware that it has previously been proposed to attach handles to cartridge fuses, none of such handles provide complete assurance of safe handling nor do they contain some of the other features shown in the present invention.

Referring now to all the views, simultaneously, the insulating body member of a cartridge fuse is shown at 10 and the metal contact members at 11 and 12. The handle member consists of a band 13, made of insulating material as for example fibre, which encircles the body part of the fuse and the ends of which are bent and shaped to form a pair of lugs 14 between which a finger grip 15 is pivotally mounted on an eyelet 16. A stop 17 is formed integral with the finger grip.

The fuse is used in the following manner: When it is desired to insert the fuse, the finger grip is maintained in the position shown in Fig.

1 and the finger grip is held between the thumb and the first finger. As the fuse is pressed in between the contacts, the fuse body 10 acts as a guard and prevents the fingers from slipping. When it is desired to remove the fuse, the finger grip is moved to the position as shown in Fig. 2, in which the stop 17 engages against the metal contact 11. When in this position a finger may be inserted between the finger grip and the body of the fuse and the fuse may thus readily be withdrawn from the fuse contact.

It frequently happens when a fuse is being removed that one end will disengage from its contacts while the other end is still engaged. This generally causes the person's fingers to slide along the fuse, or the fuse handle, and often results in serious burns. With the present handle this danger is completely eliminated inasmuch as the person's finger is guarded between the fuse body and the finger grip. In fact, advantage may often be taken of this fact. When a fuse is hard to remove, one end at a time may safely be disengaged. This is of particular advantage on large fuses.

Having described my invention and its object, what I claim as new and wish to protect by Letters Patent is:—

1. A handle for fuses of the type described comprising, a band of insulating material for encircling one end of the body member of the fuse, the ends of said band bent outwardly from said body member, a handle secured to said ends and extending towards the other end of the body member, the handle curved so that a finger may be inserted between it and the body member, and the handle pivoted to the said ends so that it may be extended from and folded against the body member.

2. A handle fuse of the type described comprising, a band of insulating material for encircling one end of the body member of the fuse, the ends of said band bent outwardly from said body member, an insulating handle secured to said ends and extending towards the other end of the body member, the handle pivoted to the ends so that it may be extended from and folded against the body member, and means associated with the handle for causing the end of the fuse opposite to that to which the band is secured to disengage from its contact before the other end is disengaged when a pull is exerted on the handle.

LOUIS LUDWIG.
